TOY CAR COUPLING WITH FORKED DETENT

Ledyard G. Kastner, New York, N. Y., and Gabriel R. Monaco, New Haven, Conn., assignors to The A. C. Gilbert Company, New Haven, Conn., a corporation of Maryland

Application October 9, 1950, Serial No. 189,142

5 Claims. (Cl. 213—211)

This invention relates to couplings for toy railway cars that differ from the common variety of couplings of miniature size by more closely resembling certain characteristics of actual full-size couplings in real railway use. Realism as well as low cost is a valuable sales asset in the modern fittings and equipment of toy railway rolling stock. The present invention not only increases realism with lowered cost but also provides various operating advantages hereinafter explained.

Toy miniature train couplings as heretofore proposed have customarily departed from the use of mutually interengaging hook structures that swing horizontally on a vertical axis, which arrangement is common practice in actual railroading. For need of greater ease in tripping and the facility for cheap quantity production in miniature sizes, toy car coupling devices are usually made to swing upward and downward about a horizontal pivot axis in their movements to mutually engage and disengage.

It is an object of this invention to make use in a toy miniature coupling of a swingable knuckle of solid block-like character serving as the only requisite movable part for effecting hooking engagement with a like swingable knuckle of a mating coupling on an adjacent car.

It is a further object to cause a miniature coupling knuckle of this character to be locked and unlocked by an extremely simple and inexpensive form of detent capable of releasing action by simple tripping means for uncoupling the cars whether such tripping means be of mechanical or magnetic nature and whether the tripping means are carried by the toy train or lie in a stationary location beside or between the track rails.

It is a further object to make the knuckle locking detent lightly sensitive to an actuating force capable of shifting it to unlocked position. This enables the source of tripping action, when stationed for instance on the road bed, to be passed over freely by the cars of a toy train with but minimum retarding resistance.

A further object is to provide the locking detent with a vertical slide bearing sufficiently elongated to guide vertical shifting movements of the detent in a steady manner and to prevent it dependably from becoming jammed or cocked when subjected to sidewise acting forces such as tripping cam action, in order that the detent may always be free to fall easily into locking position by the force of gravity alone.

A further object is to make the locking detent dependably operative when its weight is so light that the force required to lift it is almost negligible.

A contributory object is to enable a simple looped shape of bare stiff wire to constitute the entire locking detent.

Other objects have to do with provision for accommodating a miniature knuckle biasing spring to help insure completion of uncoupling action, to keep the knuckle hooks properly and yieldably positioned so as to hook themselves together automatically when two cars bump together whether on straight track or when rounding a curve, and to insure freedom of the coupling head to swing

2

somewhat in all directions responsively to the riding motion of the coupled-together cars.

These and other objects of the present improvements will be apparent in greater detail from the following description of a preferred embodiment of the invention having reference to the accompanying drawings wherein:

Fig. 1 is a perspective view of one end of a toy railway car equipped with a coupling incorporating the present improvements.

Fig. 2 is a plan view drawn larger than actual size taken partly in section on the plane 2—2 in Fig. 4 showing two of the couplings of Fig. 1 having their movable parts conditioned as when the couplings are mutually approaching and about to hook themselves together automatically.

Fig. 3 is a plan view taken partly in section on the plane 3—3 in Fig. 5 showing two mating knuckles fully hooked together to form a draft coupling between cars.

Fig. 4 is an elevation taken partly in section on the plane 4—4 in Fig. 2 showing the couplings positioned as in Fig. 2.

Fig. 5 is an elevation taken partly in section on the plane 5—5 in Fig. 3 showing the couplings positioned as in Fig. 3.

Fig. 6 is a view taken in section on the plane 6—6 in Fig. 4 looking in the direction of the arrows.

Fig. 7 is a view taken in section on the plane 7—7 in Fig. 5 looking in the direction of the arrows.

Fig. 8 is a perspective view drawn on a still further enlarged scale showing one of the knuckles removed from its coupling head.

In the drawings the coupler shank 12 is pivotally mounted on the chassis of a toy car 13 so as to swing in a horizontal arc at its end which protrudes from the car, preferably about the same vertical axis about which the wheel truck 15 swivels relatively to the car body 17. Pivotally for up-and-down swinging motion about the horizontal axis of a screw stud 14 at the terminal of shank 12 is the hollow draw head 16 having the anchorage boss 18 with which shoulder screw 14 is in tight threaded engagement. Head 16 is bifurcate in plan view affording at one of its sides vertically spaced hinge brackets 20 and at the other of its sides the camming spur 22. Spurs 22 of mating couplings cooperate in determining the automatic mutual hooking action of the knuckles 24 when shoved together by the approaching movement of the toy cars to be coupled thereby especially when cars are angularly related on a track curve.

Knuckles 24 are alike, each consisting of a solid bell crank body affording by its contours a projecting hook 26 at one end and a lockable keeper 28 at the other end. Keeper 28 comprises a vertically thick portion 30 of the knuckle which adjoins a thin portion 32 forming the floor of a recess 34 that thus has the effect of being sunk in the thick portion 30. The contours of knuckle 24 further provide another recess 36 accommodating a coil 38 of spring wire best shown in Figs. 2 and 3 as loosely surrounding a vertical pivot pin 40 that spans the space between hinge brackets 20 and is fixedly lodged therein. Knuckle 24 swings freely on pivot pin 40 which pin extends through a bearing hole 42 in the former.

End 44 of spring 38 bears against knuckle 24 in its recess 36 and the other spring end 46 bears against the inside of a side wall 48 of the hollow draw head 16. A stop surface 50 on knuckle 24 abuts against side wall 48 and limits the counterclockwise swinging movement of the knuckle to its position shown in Fig. 3. Normally, however, spring 38 urges knuckle 24 clockwise to its position shown in Fig. 2 wherein another stop surface 52 on knuckle 24 abuts against the upright terminal edge of side wall 48 of the draw head.

For positively locking the knuckle in its position shown

in Fig. 3, against the tension in spring 38, there is provided a simplified form of multi-armed detent 54 comprising a plain piece of stiff wire bent to an inverted U-shape having one branch 60 serving as an actuatable arm vertically slideable in an elongated bearing afforded by a boss 58 upstanding from the top of the hollow draw head 16 and having another branch 56 serving as a barrier arm freely slideable in vertically aligned bearing holes in the top and bottom walls 62 and 64, respectively, of draw head 16. Branch arm 56 acts as a guided barrier arm and will hold the knuckle in a locked position. On the bottom of the wire branch 60 is fixed a camming shoe 66 whose weight in addition to that of the bent wire detent is the sole force urging the detent 54 to drop to its locking position shown in Figs. 5 and 7 where the bottom end of wire branch 56 rests on the recess floor 32 thus serving as a barrier to retain knuckle 24 in its position in Fig. 5 and preventing spring 38 from swinging it to the position in Fig. 2. This positively maintains the knuckle hooks 26 of mating couplings lockingly inter-engaged until detent 54 is lifted to its knuckle-releasing position as in Fig. 4 where the bottom end of wire branch 56 rests lightly on the top surface of the thick portion 30 of keeper 28.

In operation when the ends of two cars come together, the farthest projecting end of each of hooks 26 thrusts simultaneously against the camming surface 65 of the keeper end 24 of the knuckle on the opposite coupling and this swings each knuckle against the light tension of spring 38 counterclockwise to the position in Fig. 3 whereupon each detent 54 drops into recess 34, thus locking both knuckles in hooked relation.

When in the travel of the toy train along its tracks the cam shoe 66 or other responsive element of the detent encounters a tripping agent such as short cam rail 63 stationed in or near its path between the track rails, it passes such agent without appreciably resisting train travel. In the case of cam rail 63, shoe 66 rides up over the latter which temporarily lifts wire branch 56 out of keeper recess 34 and releases the knuckle 24 for swinging movement relatively to draw head 16, whereupon spring 38 snaps the knuckle to its hook-disengaging position in Fig. 2. Here it remains until two cars are again shoved together for the automatic coupling operation before-described. Detent 54 cannot again drop into knuckle-locking position as in Fig. 5 until another automatic coupling action of the knuckle has taken place but is always ready to do so at that time.

The tripping agent 63 may take the form of track carried shiftable cams as disclosed in U. S. Patents Nos. 2,240,137, or 1,499,638, which can be shifted by an electromagnet between tripping and non-tripping positions as proposed in U. S. Patent No. 1,989,804, or the coupling may be tripped by direct electromagnetic attraction upward of detent 54 if the latter be of ferrous metal or carry an armature of such material. For the latter purpose an electromagnet may be carried by the car or on the draw head 16 in position to exert the detent releasing electromagnetic attraction at will. Also shoe 66 if magnetically polarized may be raised by magnetic repulsion when brought by train travel into close passing proximity to a permanent magnet or an electromagnet suitably stationed on the track bed between the rails, and thus activated to release knuckle 24 for uncoupling action. A cam rail such as 63 may be elongated in the direction of train travel to an extent enabling it to hold both detent shoes 66, 66 raised at the same time.

We claim:

1. A coupling for miniature cars of a toy railroad train making possible the uncoupling of cars by actuation of the coupling at the roadbed of the railroad, comprising in combination, a hollow draw head projecting endwise from the car, a hooked coupling knuckle carried at least partially within the hollow of said draw head, a vertical pivot pin anchoring said knuckle to swing horizontally in such relation to said draw head that said pivot pin withstands and transmits to said draw head the major part of the train hauling force transmitted by the coupling from car to car, and a multiple armed detent mounted to slide vertically in said draw head including a barrier arm retractably located in the path of swinging movement of said knuckle about said pivot pin and in such relation thereto that only a minor portion of said car hauling force is transmitted to said barrier arm, said detent also including a release arm laterally spaced from said barrier arm having a liftable terminal riding below said draw head in proximity to the roadbed.
2. The combination defined in claim 1, in which the said terminal of the said release arm presents a surface that is cam-shaped in relation to its path of riding travel along the said roadbed.
3. The combination with a coupling as defined in claim 1, of a roadbed extending along the course of travel of the said cars, and a tripping agent stationed on said roadbed in the path of riding travel of the said terminal of the said release arm.
4. The combination defined in claim 3, in which the said tripping agent presents an upwardly cam-shaped surface to be engaged and tracked by the said terminal of the said release arm.
5. A coupling for miniature cars of a toy railroad train making possible the uncoupling of cars by actuation of the coupling at the roadbed of the railroad, comprising in combination, a hollow draw head projecting endwise from the car, a hooked coupling knuckle carried at least partially within the hollow of said draw head, a vertical pivot pin anchoring said knuckle to swing horizontally in such relation to said draw head that said pivot pin withstands and transmits to said draw head the major part of the train hauling force transmitted by the coupling from car to car, and a multiple armed detent comprising an inverted U-shaped yoke of stiff wire mounted to slide in vertical bearings in said draw head including a vertically guided barrier arm of said yoke retractably located in the path of swinging movement of said knuckle about said pivot pin and in such relation thereto that only a minor portion of said car hauling force is transmitted to said barrier arm, said detent also including a vertically guided release arm of said yoke laterally spaced from said barrier arm having a liftable terminal riding below said draw head in proximity to the roadbed.
